COKE-OVEN BUCKSTAY STRUCTURE

Robert K. Millard, Ingomar, Pa.

Application August 22, 1944, Serial No. 550,568

3 Claims. (Cl. 202—223)

1

This invention relates to coke ovens or the like and, in particular, to a door therefor of such construction as to prevent leakage of gases from the interior of the oven.

In coke ovens as constructed heretofore, elaborate provisions have been made for sealing the space between the door and the frame surrounding it. In one form, the sealing means comprises flexible angles extending around all sides of the door and provided with screw means for seating the free edges of the angles against the door frame. This construction is expensive not only in the first cost but also in maintenance. To keep the door frame in condition for making a tight seal with the flanges of the angles, the door frame has to be cleaned periodically which is an expensive operation.

I have invented a novel form of oven door which overcomes the aforementioned objections in that it is of simple construction, requires little or no maintenance, yet affords ample protection against the escape of the gases generated inside the oven through the spaces between the door and the oven walls. In a preferred embodiment, the door of my invention comprises a metal backing adapted to engage a door frame at one end of the oven, the backing having a nose of refractory material extending inwardly therefrom adapted to fit closely between the side walls of the oven. One or both the adjacent surfaces of the nose and oven walls have grooves formed therein defining vertical flues which open at their upper ends to the interior of the oven. Any gas tending to leak from the interior of the oven between the door and the oven walls collects in these flues and is drawn upwardly therethrough and back into the upper portion of the oven from which it flows through the normal outlet for the gases evolved in the oven.

Further novel features and advantages of the invention will be pointed out in the following detailed description which refers to the accompanying drawings illustrating the preferred embodiment. In the drawings,

Figure 1 is a vertical longitudinal section, partly broken away, through a coke oven or the like equipped with doors embodying my invention;

Figure 2 is a partial section through the door and oven walls on the coke side taken along the plane of line II—II of Figure 1;

Figure 3 is a similar section through the door and walls on the pusher side taken along the plane of line III—III of Figure 1; and

Figure 4 is a partial vertical section taken along the plane of line IV—IV of Figure 1.

2

Referring in detail to the drawings, a coke oven or the like indicated generally at 10 has side walls 11 built up between spaced buckstays 12 provided with diaphragm plates 13. The buckstays are H-beams disposed with their webs normal to the length of the oven. This arrangement minimizes the warping which has been experienced heretofore because of the fact that the flanges of the I-beam usually employed which are adjacent the wall are subject to heating therefrom while the remaining flanges are subject to atmospheric cooling, resulting in differential expansion. With the construction illustrated the H-beam has the greater portion of its surface area exposed to the atmosphere, and a minimum portion exposed to the heat flowing through the wall. This latter portion furthermore, has the additional protection from the oven heat afforded by the insulation value of the brickwork between the flanges and web of the buckstay. A sufficient number of diaphragm plates may be used to increase the cooling surface to the desired extent.

The oven has a floor 14 and a roof 15. An outlet 16 is formed in the latter through which the gases distilled from the coal heated in the oven are removed. Offtake pipes (not shown) are connected to the outlet 16 in the usual manner. The roof 15 also has openings therein (not shown) through which coal is charged into the oven. Vertical flues 17 are formed in the walls 11 near the ends of the oven and crossover flues 18 connect the vertical flues of the adjacent walls to each other.

The ends of the oven are closed by doors 19 and 20 on the coke side and pusher side, respectively, of the oven. Each door is composed of a metal backing 21 adapted to engage angles 22 secured to door-frame castings 23 extending between adjacent buckstays 12. Each door frame 23 includes a sill 23a adapted to be engaged by a shoe 21a on the backing 21. A refractory nose 24 is carried on the backing 21, being held thereon by wholly embedded bars 25 and a T 26 extending vertically thereof. The sides of the nose 24 taper toward its inner end, conforming to the shape of the side walls of the furnace adjacent their ends and leaving a minimum clearance therebetween. Yokes 27 welded to the backing 21 facilitate the handling of the doors by crane hooks or the like.

The door 20 on the pusher side differs slightly from the door 19 on the coke side in that the nose 24 thereof terminates below the top of the backing 21 to permit the entrance of a leveler bar as indicated in chain lines at 28. The door

28 has an auxiliary door 29 which is opened to permit the introduction of the leveler bar.

Flues 30 and 31 are provided by grooves 32 formed in one or both the adjacent surfaces of the side walls of the oven and the noses of the doors. The grooves extend vertically from substantially the bottom of each door to the upper end thereof. The grooves forming the flues 30 curve inwardly adjacent the top of the door 18, as indicated at 33, and are open to the interior of the oven. The grooves forming the flues 31 in the side walls of the oven extend slightly above the top of the nose 24'. The lower ends of the grooves 32 are tapered as at 34.

In the coking operation, large volumes of gases are distilled from the coal heated in the oven 18 and a substantial gas pressure is built up therein. As a result, there is a tendency for a portion of the gases to flow outwardly through the spaces between the nose portions of the doors and the adjacent surfaces of the oven walls as indicated by the arrows 35. Such portions of the gases, when they reach the flues 30 and 31, will have a free exit path therealong and will thus be returned to the top of the oven on flowing out of the upper ends of the flues and will then flow through the outlet 16 along with the main mass of generated gases. It will be evident that the flues 30 and 31 thus relieve the gas pressure on the door, thereby limiting leakage, particularly when the coking operation is started. The clearance between the nose portions of the doors and the side walls of the oven should be as small as possible but it is not necessary that the backing 21 have a gas-tight fit with the flanges 22 carried by the door frame 23.

The flues 30 and 31, by carrying away gases which would otherwise leak out around the door, eliminate the nuisance of escaping smoke and the odor of the gases. More important, they prevent the hot gases from impinging on the metal backing and frame of the door, preserving them from over heating and warping. This permits a smaller clearance between the door and its frame than has been safe heretofore, without the danger of injury to the brickwork on the door by fouling on the door frame when the door is closed. The metal keying members 25 and 26 are protected from warping by heating, since they are entirely embedded as contrasted with prior constructions in which a peripheral retaining flange for the brickwork is exposed to contact with leaking gases.

As previously stated, the flues 30 and 31 may be provided by grooves formed wholly in the oven walls or wholly in the nose portions of the doors, instead of as in both, as illustrated. It may also prove desirable for the center line of the flues to depart from the plane between the sides of the nose portions and the side walls of the oven adjacent the top. This can be accomplished by making the grooves in the oven walls of an increasing depth at the top and the grooves in the nose portions of diminishing depth. This reduces the possibility that coal will be pushed into the flues by the operations of the leveler bar. The tapering of the grooves at the bottom thereof insures that any coal which does collect in the flues will fall out as soon as the doors are removed.

It will be apparent from the foregoing description that my invention is characterized by numerous advantages over coke oven doors as previously employed, particularly in respect to the simplicity of construction and the provision for

preventing leakage of the gases from the interior of the oven. The initial cost of doors according to my invention is much less than that of the doors previously used and the maintenance cost is likewise much lower since it is unnecessary to clean the outer surfaces of the door frames periodically to insure a tight fit of the door backing thereagainst. This results from the fact that the doors of my invention do not rely on a tight seal with the door frame to prevent the escape of gases.

Further economies in construction are obtained by my invention. A single collecting main will be sufficient instead of the two previously required. This eliminates also one ascension pipe, the spray and flushing system for one main and the cross-over bridge to the exhausting main.

Although I have illustrated and described but a preferred embodiment of the invention, it will be understood that changes in the construction disclosed may be made without departing from the spirit of the invention or the scope of the appended claims.

I claim:

- 25 1. In a coke oven, spaced walls defining a distillation chamber therebetween, each wall being built up between a pair of spaced, vertically disposed, metal H-beams, the webs of the beams being normal to the wall and the ends of the walls extending between the flanges of each beam, whereby the flanges at opposite sides of the web are subject to substantially equal heating, the web is protected from the oven temperature by the insulation of the wall portion between the flanges, and warping of the beams is minimized.
- 30 2. The construction as defined by claim 1 characterized by diaphragm plates fitted between the flanges of said beams on the exposed sides thereof, and spaced along the length of the beams, providing bracing for the flanges and affording additional cooling for the beams.
- 35 3. The construction as defined by claim 1 characterized by the flanges of the beams of adjacent walls defining a doorway at each end of said chamber and door-frame members secured to said flanges.

ROBERT K. MILLARD.
